Primary Examiner — Kevin K Rudzinski*Assistant Examiner* — Evans David Delesline(57) **CLAIM**

The ornamental design for a hand liquid wristband, as shown and described.

DESCRIPTION

FIG. 1 is a perspective view of a hand liquid wristband showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof; and,

FIG. 8 is a top plan view thereof.

The broken lines in the drawings depict portions of the hand liquid wristband that form no part of the claimed design.
